Primary Examiner — Mark T. Philipp(74) *Attorney, Agent, or Firm* — Scherrer Patent & Trademark Law, P.C.; Stephen T. Scherrer; Monique A. Morneau(57) **CLAIM**

The ornamental design for a tire changer, as shown and described.

DESCRIPTION

FIG. 1 is a perspective view of a tire changer showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of a portion indicated with numeric 9 in FIG. 1.

The broken lines in the drawings show portions of the tire changer that form no part of the claimed design.

The dot dash dot broken lines depict the boundaries of the detail areas and form no part of the claimed design.
